DRAFT GEAR

**Marchand B. Hall, Chicago, Ill., assignor to
Cardwell-Westinghouse Company, Chicago, Ill.,
a corporation of Delaware**

Application September 26, 1934, Serial No. 745,499

6 Claims. (Cl. 213—26)

This invention relates to shock absorbing mechanism, and, more particularly, to draft gears for railway cars, of the friction type.

One of the objects of the invention is the provision of a new and improved draft gear having a novel arrangement and construction of the wedging mechanism.

Another object of the invention is the provision of a new and improved draft gear having the wedging mechanism so constructed that the gear has a maximum extent of friction surfaces with a resultant minimum amount of wear.

A further object of the invention is the provision of a new and improved gear having a maximum capacity and so constructed that the follower casings will resist abnormal shocks without becoming distorted or broken.

A still further object of the invention is the provision of a new and improved gear having novel follower casings so constructed that they will receive a maximum capacity spring assembly and wedge mechanism, and at the same time provide an exceedingly strong column to resist abnormal buffing thrusts when the gear goes solid.

Another object of the invention is the provision of a new and improved draft gear having novel follower casings provided with a novel arrangement and means for connecting the housings together.

A further object of the invention is the provision of a new and improved draft gear which is simple in construction, of high capacity, efficient in operation and which is not likely to become injured or distorted when the gear goes solid.

Other and further objects and advantages of the invention will appear from the following description taken in connection with the accompanying drawings, in which:

Fig. 1 is a horizontal section of the center sills of a railway car showing the invention in expanded position therein, with parts in section and parts broken away;

Fig. 2 is a horizontal section through the center sills and the draft gear showing the gear in compressed position;

Fig. 3 is a section on the line 3—3 of Fig. 1; Fig. 4 is a section on the line 4—4 of Fig. 1; Fig. 5 is a section on the line 5—5 of Fig. 1; Fig. 6 is a perspective view of one of the followers;

Fig. 7 is a perspective view of the other follower; Fig. 8 is a perspective view of one of the wedge blocks;

Fig. 9 is a perspective view of one of the wedge members; and

Fig. 10 is a perspective view of the other wedge member.

The continual increase in the size or weight of the cars from time to time necessitates a corresponding increase in capacity for the draft gears. This increase in capacity becomes quite a problem due to the limited space available for the installation of the gear. For instance, an increase in the cross sectional area of the turns of the main resistance spring will increase the capacity of the gear, but this increase in the cross section of the turns means that with the conventional pitch the spaces between the turns will be reduced to such an extent that the spring will not have the proper travel, and, hence, will go solid before the opposed casings come in contact, thereby permanently injuring the spring. The space available for the reception of the gear is such that the gear must be so constructed as to accommodate the increase in size or weight of the cars without an increase in the dimensions of the draft gear pocket. In the present invention the gear is so constructed that it not only has the dimensions of the conventional draft gear but also has sufficient capacity together with a proper amount of travel for both the springs and the gear casings to accommodate cars of different weights and capacities.

Referring now to the drawings, the reference characters 10 and 11 designate the center sills of a railway car having the draft lugs 12 and 13 and the buffing lugs 14 and 15 forming the draft gear pocket 16, within which is mounted the draft gear 17, as is usual in such constructions. The draft gear comprises what for convenience of description will be termed the outer or forward follower 18 and the inner or rear follower 19. These followers are hollow. The forward or outer follower 18 has both ends open while the rear or inner follower 19 preferably has its inner end closed as at 21 (see Figs. 1 and 6).

A follower plate 22 is preferably inserted between the outer end of the follower 18 and the draft lugs 12 and 13 which forms a closure for the outer end of the forward casing. The adjacent ends of these casings are rectangular. The forward casing has the depressed walls 23 at each corner of the gear forming the corner flanges 24 which are apertured for receiving bolts 25 for limiting the expansion of the gear, as will presently appear. The rear follower 19 is also provided with the depressed walls 26 that form corner flanges 27 which are also apertured for receiving the bolts 25. These bolts extending through the two sets of securing flanges 24 and 55

27 are adapted to limit the separation of the gear when the same is not in position in the draft gear pocket. The depressed walls 23 at the four corners of the forward housing are preferably 5 arranged on the arc of a circle, the diameter of which is substantially the same as the distance between the inner surfaces of the upper and lower walls of the gear whereby a spring 28 of maximum diameter may be received in the recess 10 formed by said walls.

It will be noted that by depressing the walls 23 to form flanges, additional projections on the follower with a consequent reduction in the dimensions of the casings will not be necessary for 15 the accommodation of the bolts 25, and, consequently, the spring 28 may be the maximum diameter that can be employed in the draft gear pocket. This is considered an important feature of applicant's invention because it permits the 20 use of a spring of the maximum diameter with a consequent increase in capacity.

The rear follower also has its intermediate corner walls 26 curved and depressed for accommodating the wedging mechanism, as will presently appear.

Suitable means are provided for yieldingly resisting the compression of the gear. In the form of construction shown, the forward casing 18 is provided with a pair of inwardly facing 30 wedge faces 29 and 31 and the rear follower is similarly provided with inwardly facing wedge faces or inclined surfaces 32 and 33 at its forward end for cooperating with the wedge faces or inclined surfaces 29 and 31 for engaging wedging 35 blocks, as will presently appear.

Each of the wedge faces on the two casings is curved transversely of the casing. These wedging faces are curved to afford clearance for the bolts 25. By curving these faces, weakening the 40 housing at the intersection of the depressed walls and the securing lugs or flanges is also avoided.

Furthermore, from an inspection of Fig. 5, it will be apparent that the curved wedging faces together with the curved wedging elements will 45 properly position those elements. This is considered an important feature of the invention since this arrangement will prevent skewing of the wedging elements, thereby insuring smooth 50 operation of the gear on release as well as on compression.

A pair of wedge blocks 34 and 35 is provided for cooperating with the curved surface on the inner ends of the follower casings. Each of these blocks is provided with a pair of wedging faces 55 36 and 37 on its outer side and with a pair of wedging faces 38 and 39 on its inner side (see Fig. 8). The blocks are curved transversely to the gear to conform to the curvatures of the wedging faces on the adjacent ends of the follower casings. A pair of wedging members or 60 elements 41 and 42 (see Figs. 9 and 10) are provided for cooperating with the inner wedging faces 38 and 39 of the blocks 34 and 35, respectively.

65 The rear wedge member 41 is provided with the inclined wedging faces 43 and 44 which are curved transversely of the gear for engaging the corresponding curved wedge faces 38 of the blocks 34 and 35. This block is provided with an axial opening 45 for receiving the retaining bolt 70 46 (see Fig. 2), as will presently appear. The opening 45 is countersunk at its outer end and is angular in form for receiving the head 47 of the bolt and preventing its rotation.

75 The forward wedge member 42 is likewise pro-

vided with wedging faces 48 and 49 at the sides thereof for engaging the wedge faces 39 on the wedge blocks 34 and 35. The wedging faces 48 and 49 of the block 42 are also curved transversely of the gear for conforming to and frictionally engaging the wedge face 39 of the block 34. The forward end of the block 42 is provided with an axial opening 50 which is countersunk as at 51 for providing a seat for a spring, as will presently appear.

10 Suitable means are provided for resiliently resisting the separation of the wedge members 41 and 42 when the gear is compressed. In the form of construction shown, a plurality of springs are employed for this purpose. These springs are 15 arranged concentrically on the retaining bolt 46.

In the form of construction selected to illustrate one embodiment of the invention, three concentrically arranged springs 52, 53 and 54 are employed. The inner spring 54 is adapted to 20 seat in the recess or countersunk portion 51, and the intermediate and outer springs 53 and 52, respectively, seat on the outer face of the wedge member 42. Since the springs have but little clearance between them, the inner spring 54 25 seated in the countersunk or recess 51 will assist in positioning said springs. Furthermore, since the outer spring 52 is adjacent to the curved walls 23, those walls will assist in centering the outer spring. The outer ends of the springs seat on 30 a cap 55 secured on the outer end of the rod or bolt 46. To compensate for the depression 51, the cap 55 may be provided with a hub portion 56 on which the inner spring 54 is seated.

When the gear is assembled, the parts may be 35 held in proper position by the bolts 25 at each corner of the gear. These bolts are adapted to engage the apertures in the corner flanges of the two follower casings, as is clearly shown in Fig. 3 of the drawings. In order to increase the travel 40 of the gear without decreasing its capacity, additional space is provided for accommodation of the springs. To provide this additional space, the wedge member 42 is provided with a recess 45 57 which is adapted to receive the corresponding projection 58 on the wedge member 41. This recess and projection are arranged transversely to the wedging faces so as to not unduly weaken the wedge member 42. By means of this arrangement, a longer space is provided for the springs 50 whereby springs having turns of greater cross sectional area and consequent greater capacity may be employed without decreasing the travel 55 of the springs and without foreshortening the length of the wedging faces of the wedging members 41 and 42.

The casing 18 may, if desired, be provided with intermediate transverse ribs 59 which have their inner edges curved to conform to the curvature of the outer spring 52 and assist in preventing 60 buckling of said spring.

In the operation of the device, when the gear is compressed, either upon pull or upon buff, the follower casings are forced toward each other which through their adjacent wedging faces will 65 force the wedge blocks 34 and 35 inwardly and this in turn will tend to separate the wedge members 41 and 42 against the tension of the springs 52, 53 and 54. The friction of the wedge faces will absorb a great proportion of the force of 70 buff or pull. Upon release of the pressure, the springs will force the parts to their normal inoperative position, as shown in Figs. 1 and 4. Upon abnormal compression of the gear, the adjacent end of the casings will abut each other, 75

and the shape of the top and side walls along with the curved walls of the casing will form a reinforced column that will prevent damage or distortion.

5. I claim as my invention:—

1. In combination, a pair of followers, a pair of curved wedge blocks within said followers, said blocks having inner and outer curved wedging faces, a pair of concave wedging faces on 10 each follower engaging the outer curved faces of said blocks, a pair of opposed wedging members between said blocks on the center line of said gear and having convex wedging faces engaging the inner wedging faces of said blocks, one of 15 said members having a projection engaging in a recess in the other member when said gear is in release position, a bolt extending axially through said members, a plurality of springs on the free end portion of said bolt and a spring seat on the 20 end of said bolt outwardly of said springs.

2. In a draft gear, a pair of follower casings having wedging faces on their meeting edges, a pair of wedging blocks engaging said faces, a pair of wedge members between said blocks, one of 25 said members having a projection engaging in a recess within the other of said wedge members when said gear is expanded, a bolt extending axially through said members and springs on said rod for resiliently resisting the separation of said 30 members when said gear is compressed.

3. In a draft gear, a sectional casing comprising a pair of chambered followers provided at their adjacent edges with wedge faces, each of said faces being curved transversely to the axis 35 of said gear, a pair of cooperating wedge blocks extending into the adjacent ends of said followers, each of said blocks being curved to conform to the curvature of the wedging faces on said followers, a pair of wedge elements, one in 40 each casing having curved wedging faces engaging corresponding inner curved wedging faces of said blocks, said elements having their inner ends lapping when the gear is expanded, a bolt extending through said elements along the axis of 45 said gear, and spring members on one end of said rod for resiliently resisting the separation

of wedge elements when said gear is compressed, said rod and springs being housed within said casing.

4. In a draft gear, a pair of chambered followers having opposed wedging surfaces facing laterally inwardly, said surfaces being curved, a pair of curved wedge blocks engaging said wedging surfaces, and a pair of wedging elements each having convex wedging faces engaging said blocks, the inner ends of said elements extending past each other when said gear is in normally expanded position, a retaining bolt extending axially through said elements and a spring seat on one end of said bolt and a plurality of springs between said seat and one of 10 said elements, one of said elements having a counter-bore for receiving the head of said bolt and the other of said elements having a counter-bore for receiving the inner end of one of said 15 springs, said springs constituting the sole means 20 for resiliently resisting the compression of the gear and for restoring the parts to normal position after compression.

5. In a draft gear, a pair of chambered followers having their adjacent ends provided with 25 wedging faces, a pair of wedge blocks engaging said faces, a pair of opposed wedge members engaging said blocks, the adjacent portions of said members having cooperating interengaging portions that are adapted to engage when said gear 30 is normally expanded, and means for resiliently resisting the separation of said members when said gear is compressed.

6. In a draft gear, a pair of followers having their adjacent ends provided with wedging faces, 35 mechanism including spring pressed wedging means engaging said faces for frictionally resisting the compression of said gear, said means comprising a plurality of wedge elements, certain of which has a recess and another a projection for engaging in said recess when said gear is compressed whereby said elements occupy a 40 minimum of space and are provided with extended friction faces.

45
MARCHAND B. HALL.
